UNITED STATES PATENT OFFICE.

GEORGE A. LUTZ, OF PLAINFIELD, NEW JERSEY, ASSIGNOR TO AMERICAN CIRCULAR LOOM COMPANY, OF PORTLAND, MAINE, A CORPORATION OF MAINE.

SUPPORT FOR ARTICLES TO BE ELECTROPLATED.

1,022,853.

Specification of Letters Patent.

Patented Apr. 9, 1912.

Application filed January 7, 1911. Serial No. 601,468.

To all whom it may concern:

Be it known that I, GEORGE A. LUTZ, a citizen of the United States, and resident of Plainfield, in the county of Union and 5 State of New Jersey, have invented certain new and useful Improvements in Supports for Articles to be Electroplated, of which the following is a specification.

The object of my invention is to provide 10 simple and efficient means to support pipes, conduits, and analogous articles within an electroplating tank or apparatus in such manner that the surface of the article throughout its entire length will be subjected 15 to the electrolyte and current, and my invention has particular reference to supporting pipes that are provided with threads at both ends so that the threads will be exposed at all parts to the electrolyte. 20 My invention comprises novel details of improvement and combination of parts that will be more fully hereinafter set forth and then pointed out in the claims.

Reference is to be had to the accompanying 25 drawings forming part hereof, wherein,

Figure 1 is a partly broken side elevation illustrating my improvements; Fig. 2 is a view at right angles to Fig. 1; Fig. 3 is an enlarged broken detail of the support; Fig. 30 4 is a section on the line 4, 4, in Fig. 3; and Fig. 5 is a section on the line 5, 5, in Fig. 3.

Similar numerals of reference indicate corresponding parts in the several views.

The numeral 1 indicates a supporting 35 member shown in the form of a rod adapted to be suspended from any suitable support, as from a hanger 2. Rod 1 is provided with a hook or eye, as shown at 1^a, to detachably engage a hook or eye on the hanger 2, 40 shown at 2^a, the hanger 2 being shown depending from a rod 3 of a cathode or supporting frame of an electroplating apparatus, although rod 1 may be supported in any suitable manner from such cathode or 45 frame. Rod 1 is adapted to be passed through the article to be plated, such as pipe 4, and at the lower end rod 1 is provided with a detachable or adjustable support 5 with for the pipe. For this purpose I have shown 50 support 5 in the form of an angle-plate having a slot or opening 5^a receiving the lower end of rod 1. The slot 5^a enters support 5 at the angle whereby part of the slot enters each wall of the angle-plate 5. I have shown 55 slot 5^a as having an enlarged part 5^b in one

wall and a reduced part 5^c in the other wall communicating at the angle of the plate for the passage laterally through the slot of the lower end of rod 1. Rod 1 is provided with a head 1^b at its lower end, beyond the neck or reduced part 1^c of the rod, the part 5^b of slot 5^a being sufficiently large to receive head 1^b while the part 5^c of said slot is smaller than said head, but receives the neck 1^c of rod 1, whereby support 5 may be 60 hung upon the rod, 65

In using my improvements the pipe, tube or article to be plated is passed over rod 1, the support 5 is moved sideways with respect to the lower end of rod 1 so that the head 1^b and neck 1^c pass through the corresponding parts of slot 5^a, whereby support 5 is hung upon rod 1, and then the pipe is lowered to rest or stand upon support 5. 70 To remove the pipe it is merely necessary to move the support 5 sideways to detach it from the rod 1. By having the support 5 of metal it forms a conductor between the pipe and the rod 1. 75

In accordance with my improvements the 80 pipes or the like to be plated may be readily applied to or removed from the supporting rod, and when supported upon the rod the exterior surface of the article will be fully exposed to the electrolyte in the tank of the 85 electroplating apparatus into which the articles will be lowered. This will be found of advantage, particularly where pipes or tubes are to be electroplated throughout their full 90 length and are provided with screw threads at their ends which are also to be electroplated, as distinguished from pipe supporting devices known to me which are provided with screw threaded sockets into which the threads at the ends of the pipes are screwed 95 for supporting the pipes, whereby a portion of the threads at least are thus necessarily left unplated.

My improvements will be found advantageous 100 in apparatuses for electroplating pipes to serve as conduits for conductors in electric wiring systems, since it is desirable, where the pipes are electroplated and provided with threads at one or both ends, to have such threads electroplated throughout. 105

Having now described my invention what I claim is:

1. A supporting device of the character described comprising a rod provided at its lower end with a head, and a support in an 110

gular form having a slot open through the angle of the support and extending partly into both walls of the support adapted to rest upon said head.

5 2. A supporting device of the character described comprising a rod having a head at the lower end and a reduced neck above the head, combined with a plate in angular form having a slot opening through the angle of said plate and extending into both its walls, one part of the slot being adapted to receive said head and the other part of the slot being adapted to receive said neck.

10 3. A supporting device of the character described comprising a rod having a head at

the lower end and a reduced neck above the head, combined with a plate in angular form provided with a slot extending through the angle into the walls of the plate; the slot being provided with an enlarged portion in one wall of the plate to receive said head and with a reduced portion in its other wall to receive said neck. 20

Signed at New York city, in the county of New York, and State of New York, this 4th 25 day of January, A. D. 1911.

GEORGE A. LUTZ.
